UNITED STATES PATENT OFFICE.

ERNEST REINFELD, OF LUDLOW, KENTUCKY.

RECEPTACLE-CLOSURE.

1,811,091.

Specification of Letters Patent.

Patented July 22, 1919.

Application filed January 26, 1917, Serial No. 144,717. Renewed April 5, 1919. Serial No. 287,927.

To all whom it may concern:

Be it known that I, ERNEST REINFELD, a subject of the Kaiser of Germany, residing at Ludlow, in the county of Kenton and State of Kentucky, have invented new and useful Improvements in Receptacle-Closures, of which the following is a specification.

This invention relates to closures for bottles, cans and like receptacles, and aims to provide a cap designed to coöperate with the mouth of the receptacle to permit said cap to be easily and quickly associated with or removed from the receptacle, and when applied securely held in position and providing an air-tight closure.

The nature and advantages of the invention will be better understood when the following detail description is read in connection with the accompanying drawing, the invention residing in the construction, combination and arrangement of parts as claimed.

In the drawing forming part of this specification like numerals of reference indicate similar parts in the several views and wherein:—

Figure 1 is a fragmentary view of a receptacle with the cap removed.

Fig. 2 is a detail view of the cap partly in section.

Fig. 3 is a sectional view taken through the receptacle with the cap positioned thereon, and Fig. 4 is a detail view.

The use of the invention in connection with a can is sufficiently characteristic of its utility and admirably illustrates the invention, and will constitute one of its most useful applications. For this reason the description is addressed to the coöperation of the closure with the neck or mouth of a can, but it is to be understood however that the invention is applicable to other forms of receptacles, and that such general application is contemplated by the claim.

Referring to the drawing in detail 10 indicates a can or other receptacle, and 11 the neck or mouth thereof, which latter is preferably tapered. The neck 11 is provided at its opposite sides with bayonet grooves, the vertical branches 12 of which are adapted to receive projections carried by the cap shown in Fig. 2, for locking the cap in position and with a view of providing an air-tight closure.

The cap is indicated generally at 13 and is of cross sectional configuration to accommodate itself to the neck 11 of the receptacle. The lower edge of the cap is bent inwardly as at 14 to hold a resilient annulus 15 associated with the cap. The annulus 15 at diametrically opposite points projects through openings 16 in the inwardly turned edge portion 14 of the cap, the resilient projections 16 being adapted to be received within the grooves 12 when the cap is associated therewith. When the neck 11 is tapered as shown in Figs. 1 and 3, the grooves 12 are formed to provide an uninterrupted circumference at the mouth as shown.

In practice the projections 16 enter the vertical branches 12 of the bayonet grooves formed in the neck, upon the initial application of the cap to the receptacle. When the cap has been adjusted a predetermined distance, upon the neck 11, the cap is given a slight turn in the proper direction to move the projections 16 into the laterally disposed branches 12' of said groove whereby the cap is effectively locked upon the receptacle. The laterally disposed branches 12' of said grooves are slightly inclined to effectively draw the closure to a full closed position with a view of providing an air-tight connection between the closure and the receptacle.

While it is believed that from the foregoing description the nature and advantages of the invention will be readily apparent I desire to have it understood that I do not limit myself to the exact construction and arrangement of parts herein shown and that such changes may be resorted to when desired as fall within the scope of what is claimed.

What is claimed is:—

A receptacle having a neck provided with opposed bayonet grooves, each groove having a straight vertically disposed branch opening adjacent the upper edge of the neck, 100 a cap, a resilient annulus secured within the cap adjacent its lower end, and offset projections extending from said annulus inwardly of said cap and adapted to be fitted in said grooves to hold the cap in position 105 on the neck.

In testimony whereof I affix my signature.

ERNEST REINFELD.
